(Cl. D71—1)

To all whom it may concern:

Be it known that I, Edgar P. Rhodes, a citizen of the United States, residing at Greiner Road, Clarence, county of Erie, State of New York, have invented a new, original, and ornamental Design for an Airplane, of which the following is a specification, reference being had to the accompanying drawings, forming a part thereof.

Figure 1 is a top plan view of an airplane showing my new design;

Figure 2 is a side elevational view;
Figure 3 is a front elevational view; and
Figure 4 is a rear elevational view thereof.

I claim:

The ornamental design for an airplane, as shown.

EDGAR P. RHODES.
